UNITED STATES PATENT OFFICE.

GEORGE THOMPSON, OF HOUGHTON, MICHIGAN.

WATER-TUBE BOILER.

SPECIFICATION forming part of Letters Patent No. 666,858, dated January 29, 1901.

Application filed April 14, 1900. Serial No. 12,801. (No model.)

To all whom it may concern:

Be it known that I, GEORGE THOMPSON, a resident of the city of Houghton, county of Houghton, State of Michigan, have invented 5 certain new and useful Improvements in Water-Tube Boilers, of which the following is a full, clear, and exact description.

The present invention has for its object to provide an improved construction of boiler 10 for the generation of steam for power, for heating, or other purposes; and distinctive features of my invention will be found to consist in the construction whereby a very large area of heating-surface is attained within 15 very small compass, the arrangement being such that the heat from the fuel shall be most effectively distributed and utilized before its final passage to the stack.

My invention is further characterized by 20 the improved means whereby an exceedingly compact and efficient boiler is secured that is complete and ready for use as it leaves the factory and the construction of which is such that repairs or replacement of parts can be effected at a minimum cost.

My invention is hereinafter described, and its novel features are more particularly pointed out in the several claims at the end of this specification.

30 Figure 1 is a view in side elevation of my improved boiler. Fig. 2 is a view in central vertical longitudinal section. Fig. 3 is a front view. Fig. 4 is a view in vertical section on line 4 4 of Fig. 2. Fig. 5 is a view in horizontal section on line 5 5 of Fig. 3. Fig. 6 is a view in vertical cross-section on line 6 6 of Fig. 5. Fig. 7 is a detail view in vertical cross-section, showing more particularly the manner of supporting the inner end of the 35 feed-water heaters. Fig. 8 is a detail view in cross-section through the front ends of the feed-water heaters, the pipes extending between the heaters being shown in elevation.

Upon a suitable foundation A is mounted 45 a metal bed-plate B, whereon my improved boiler is sustained. By reference more particularly to Figs. 2 and 4 of the drawings it will be seen that that part of the bed-plate B that extends over the ash-pit a serves to support the damper-plate C, whereon rests a suitable damper-plate c, and is provided with transverse grate-bar supports d, that serve to

sustain the grate-bars D of the furnace. At the rear of the grate-bars D rises a transverse bridge-wall A', preferably braced by an angular back-plate a², (see Fig. 2,) this bridge-wall dividing the rear of the furnace and causing the products of combustion to rise as they pass from the fuel-chamber. 55

My improved boiler is of a type that may 60 be appropriately termed a "self-contained" boiler, and the walls of the boiler are shown as resting upon the bed-plate B. The side and end walls of the boiler are formed of iron or steel plates held at proper distance 65 apart to form a chamber that extends around the fuel-chamber and the furnace proper and the space through which the products of combustion must travel as they pass to the furnace-stack. As shown, the bottom of the 70 water-chamber, that is formed by the plates comprising the sides and end walls of the boiler, consists of a U-shaped or channel bar E, to the upturned flanges of which are riveted the lower edges of the plates that comprise the boiler-walls. The front wall of the 75 boiler is shown as formed of the plates E' and E², the back wall being composed of the plates E³ and E⁴ and the side walls being formed, respectively, of the plates F F' and F² F³. 80 The top of the water-chamber formed in the front, rear, and side walls of the boiler is closed (except at the points hereinafter indicated) by top plates E⁵, preferably of inverted-U-shaped channel-bars, the flanges of these 85 top plates being riveted to the upper edges of the plates that comprise the boiler-walls.

By reference more particularly to Figs. 2 and 4 of the drawings it will be seen that the plates that comprise the boiler-walls are 90 braced at different points by stay-bolts e and e'. The stay-bolts e are solid bolts, but preferably the stay-bolts e' are tubular bolts entering threaded openings in the plates of the boiler-walls, the purpose of employing 95 tubular stay-bolts e' at such points being to enable the dust to be blown from off the water-tubes within the boiler, as will presently more fully appear.

Upon the front and rear walls of the boiler 100 is supported the steam-drum G, this drum being formed of boiler-plate and with closed ends g g', as shown in the drawings. One end of the drum G is provided with a man-

hole g^2 , that is closed by an interior cover g^3 , from which extends a bolt g^4 , that passes through a crab or spider-frame g^5 , the legs of which bear against the outer face of the end 5 of the drum. The bolt g^4 is furnished with an adjusting-nut, whereby the cover g^3 may be drawn tightly to place. Adjacent its front and rear ends the drum G is formed with openings g^6 , that communicate with the corresponding chambers between the plates or shells that comprise the front and rear walls of the boiler. Across the openings g^6 are extended stay bars or plates i , that serve to strengthen the drum at such points. By reference to Figs. 2 and 4 of the drawings it will be seen that the upper ends of the plates comprising the front and rear walls are flanged, as at e^3 , and these flanges are riveted to the drum G, and to the drum is also connected 10 the upper end of the top channel-plate E^5 . The top channel-plate E^5 is bent upward to conform to the outlines of the front and rear wall-plates, that rise centrally about the openings g^6 of the drum G.

25 Adjacent the bottom of the drum G are formed a series of holes g^8 , and a corresponding series of holes are formed adjacent the upper edge of each of the side walls F' and F^2 , and between these holes of the side walls 30 and drum extend the transverse tubes $H' H'$, by which a circulation of water is secured at such points. Preferably the tubes $H' H'$ are arranged out of alinement, as seen in Fig. 4, to insure a more effective distribution and exposure of the tubes to the action 35 of the products of combustion. Between the side walls F' and F^3 of the furnace also extend the series of transverse pipes J, the arrangement of which is preferably that shown 40 in Fig. 2 of the drawings—that is to say, the pipes J are arranged in zigzag manner for more effective exposure of the water therein to the products of combustion. In like manner also the inner plates of the front and rear 45 walls of the furnace are connected by a series of water-tubes K, the arrangement of which tubes is preferably that indicated in Fig. 4 of the drawings, and beneath the rear portion of the tubes K and connecting the inner plates 50 F' and F^3 of the side walls of the boiler extend the transverse water-tubes L, that are preferably arranged, as shown, in the path of the products of combustion as the latter pass over the bridge-wall A'. Above the fuel-chamber and extending to a distance back 55 of the bridge-wall A' is the transverse plate or wall M, of fire-brick or like refractory material, this plate being preferably located above the bottom row of longitudinal tubes 60 K, and above the upper row of these tubes K is arranged a similar plate or wall M', of fire-brick or like material, that extends from the rear wall of the boiler to a point about midway above the fuel-chamber. The purpose 65 of the plates or walls M M' is to effectively serve in guiding the products of combustion rearwardly between the series of trans-

verse tubes L, thence forwardly between the longitudinal tubes K, and thence rearwardly between the upper series of transverse water-tubes J as the products of combustion travel toward the smoke-stack of the furnace. By reference to Fig. 4 it will be seen that the transverse plates or walls M M' do not extend entirely from side to side of the boiler-walls, 70 but open spaces m are left at each side, so that a portion of the products of combustion may rise at the sides, thus more effectively distributing the heat upon the side walls and around the water-tubes adjacent thereto. 75

At the sides of the steam-drum G extend the cylindrical water-drums N and N'. These drums are of plate metal, their inner ends being permanently closed by caps n , while their outer ends are closed by removable covers n' , the flanges n^2 of which are conveniently bolted to corresponding flanges formed at the outer ends of the heaters. The front ends of the drums N N' rest upon the channel-plates E^5 , that extend between the top 80 edges of the plates E' and E^2 of the front wall of the furnace, and the rear ends of each of the drums N N' are preferably supported by brackets n^4 , that rise from the channel-plates E^5 , that cover the chambers of the side walls 85 of the boiler, (see Figs. 5 and 7,) these brackets engaging arms or brackets n^5 , that are bolted to the outer sides of the drums N N'. To the inner sides of these drums N N' are bolted angular brackets n^6 , (see Fig. 7,) that 90 are engaged by slotted strap-irons n^7 , the upper ends of which are secured, as at n^8 , to the side walls of the drum G. Manifestly the drums N N' may be supported in other ways; but I prefer the construction shown, 95 as it leaves the inner ends of the drums thoroughly exposed to the action of the products of combustion.

Over each of the drums N N' extends an arch-plate P, preferably provided with asbestos lining p , and the lower edge of each arch-plate is bolted to a channel-bar p' , that extends along and is secured to the U-shaped channel E^5 , that unites the plates forming the side walls of the boiler. The upper inwardly-extending edges of the arch-plates P 110 abut against and are suitably secured to the wall of the drum G, and the rear ends of the arch-plates P are fastened to the front face of the smoke-flue R, that rises from the rear 115 of the boiler. By reference to Figs. 1 to 4 of the drawings it will be seen that the smoke-flue R is arched above the drum G, the legs of the smoke-flue extending upon opposite sides of the drum. The back and side walls 120 of the smoke-flue, as shown in Fig. 5, rest upon the U-shaped channel-bar E^5 . The front walls of the smoke-flue extend over and are secured to the rear ends of the arch-plates P, and the inner wall r of the smoke-flue has 125 its downwardly-extending ends bearing against the wall of the drum G. (See Fig. 4.) Suitable angle-bars r' , that extend around the angles of the smoke-flue, serve to stiffen 130

the parts and more securely unite them together. It will thus be seen that as the products of combustion pass around the front edge of the horizontal plate M' they will rise up between the tubes J and $H H'$ and around the drums $N N'$ and will pass rearwardly into the lower sections of the smoke-flue R . It will be understood, of course, that the upper part of the smoke-flue will be united in suitable manner with the stack.

In order to permit the water-tubes to be readily placed in position and to be removed when repairs become necessary, I form the outer walls of the boiler with a series of holes arranged at points opposite the outer ends of the water-tubes. Thus by reference to Fig. 2 it will be seen that a series of holes are formed in the outer plates or shells E' and E^2 of the front and rear walls at points opposite the ends of the water-tubes K . These holes are normally closed by interior plugs or covers k' , from each of which extends a bolt k^2 , that passes outward through a crab or spider-frame k^3 , each bolt being provided with a threaded nut or washer k^4 . By withdrawing the crab or spider-frame k^3 the corresponding cover k' can be removed and access may be had to the end of the corresponding water-tube K . In order to cover the groups of crabs or spider-frames k^3 , I prefer to attach to the front and rear walls of the boiler frames e^8 , having hinged doors e^9 , one of which is shown in Fig. 3 of the drawings. In like manner also the outer plates of the side walls F and F^2 (see Fig. 4) are formed with a number of openings at points opposite the water-tubes L , these openings being closed by plugs or covers l' , having bolts l^2 extending therefrom, these bolts passing through crabs or spider-frames l^3 and being provided with threaded nuts l^4 . In order to permit the plugs or covers l' to be conveniently passed through the plate, I prefer to form several of the lowest holes of the group of oblong shape and of such size as will permit the passage of the covers therethrough. The side walls are shown as having frames e^{10} extending around the groups of crabs or spider-frames l^3 , and the frames e^{10} are closed by plates e^{11} . The plates e^{11} are shown as formed with inwardly-turned flanges e^{12} , that engage the outwardly-turned flanges of the frame e^{10} , (see Fig. 4,) the plate e^{11} being arranged to slide to position upon the frame e^{10} when the flanges of the plate and frame are interlocked. All of the water-tubes are set at an inclination, and the arrangement and location of the tubes are preferably as shown, although manifestly this arrangement and location may be varied without departure from the spirit of the invention.

In order to deliver the feed-water to the boiler, the arrangement of pipes next to be described is preferably adopted. The water is admitted from the source of supply by pipe S first to the drum N , the pipe S extending

rearwardly within the heater, as clearly shown in Fig. 5 of the drawings. From the upper part of the front of the drum N the water passes by pipe S' to the drum N' . By reference to Figs. 5 and 8 of the drawings it will be seen that while the pipe S' takes the water from the front end and from adjacent the top of the drum N it delivers it to the rear portion of the drum N' . From the front end of the drum N' leads a pipe S^2 , that extends through the front end of the drum G to the rear of the drum and has a downwardly-extending end that opens into the space g^6 (see Fig. 5) at the rear of the drum. The drums $N N'$ by this arrangement serve to increase the water-heating surface of the boiler. To the bottom of each of the drums $N N'$, adjacent its front, is connected a blow-off pipe T , this pipe serving to remove the sediment, &c., when the drums are to be cleaned.

By reference more particularly to Figs. 2 and 3 of the drawings it will be seen that the fire-box or fuel-chamber of the boiler has openings therein for the delivery of fuel onto the grate-bars, these openings being in suitable number and being closed by hinged doors U , U' , U^2 , and U^3 . Around the openings and between the plates E' and E^2 extend the frames u , that are riveted to the inner and outer plates E' and E^2 of the front wall. In like manner also the rear wall of the boiler has an opening e^{14} , through which access may be had to the interior of the lower part of the boiler in order to permit the same to be cleaned. This opening e^{14} is closed by a suitable cover e^{15} , and around the opening e^{14} extends a frame u , corresponding to the frames that extend around the door-openings at the front of the boiler. Each of the frames u in the front and rear walls consists of a plate having a flange u' , that is riveted to the adjacent outer plate of the boiler-wall, and the inner plate of the front wall of the boiler has outwardly-extending flanges, as indicated by dotted lines in Fig. 2, that enter the frames u , while the inner plate of the rear wall is formed about the opening e^{14} with an outwardly-extending flange e^{17} , that enters the frame u , located at such point.

At one side of the boiler is located the water-column tube V , with glass gage v for determining the amount of water in the drum, and the top of the water-column tube V is connected by a pipe V' with the upper part of the steam-drum G , while the lower part of the tube V is connected by a pipe V^2 with the lower part of the boiler.

The top of the steam-drum G is shown as provided with a steam-delivery port W and with a safety pop-valve Y . Beneath the delivery-opening W is preferably arranged a baffle-plate w , that serves to prevent the discharge of water and foam with the dry steam through the discharge-opening W .

While I have described what I regard as the preferred embodiment of my invention, it is obvious that the details of construction

hereinbefore described may be varied by the skilled mechanic within wide limits without departing from the spirit of the invention, and it is obvious also that features of the invention may be employed without its adoption as an entirety.

From the foregoing description it will be seen that when fire is built upon the grate-bars D the products of combustion will pass up over the bridge-wall A' and around the transverse tubes L, thence around the rear edge of the horizontal plate M, (a portion of the products also passing up at the sides of the plate M,) and thence between the tubes K and around the front end of the plate M', as well as through the narrow spaces at the side of said plate M'. The products of combustion rising above the plate M' will travel toward the smoke-flue R, but in so doing will pass around the transverse water-tubes L and H H' and will rise also around the drums N N'. By this construction the heat of the fuel and the products of combustion are most effectively utilized before they pass to the furnace-stack.

Having thus described my invention, what I claim as new, and desire to secure by Letters Patent, is—

1. A water-tube boiler having a continuous vertical wall with a continuous water-space therein, said wall forming and entirely surrounding the fire-box and combustion-chamber, partitions in said combustion-chamber forming a continuous zigzag passage for the products of combustion and transverse water-tubes connecting the opposite sides of said continuous wall, passing through said passage and opening into said continuous water-space.

2. A water-tube boiler having front, rear and side vertical walls with a continuous water-space through said walls, said walls forming and entirely surrounding the fire-box and combustion-chamber and transverse water-tubes connecting said front, rear and side walls, passing through said combustion-chamber and opening into said continuous water-space.

3. A water-tube boiler having front, rear and side vertical walls with a continuous water-space therein forming and entirely surrounding a fire-box and combustion-chamber, a steam-drum located at the top of the boiler and separate water connections between said drum and each of said front, rear and side walls.

4. A steam-boiler having chambered walls surrounding the fire-box and the space through which the products of combustion pass and having a lower series of transverse water-tubes, an upper series of transverse water-tubes and an intermediate series of longitudinal water-tubes arranged in the path of travel of the products of combustion, said water-tubes connecting opposite points in the chambered walls of the boiler.

5. A steam-boiler having chambered walls

surrounding the fire-box and the space for the passage of products of combustion and having two transverse plates arranged at different elevations between the walls, the free ends of said transverse plates being out of vertical alinement to make a sinuous passage for the products of combustion, a series of water-tubes located below the lowermost transverse plate, a series of transverse water-tubes located above the uppermost transverse plate and a series of longitudinal water-tubes located between said transverse plates.

6. A steam-boiler having chambered walls surrounding the fire-box and the space for the passage of products of combustion and having two transverse plates arranged at different elevations between the walls, the free ends of said transverse plates being out of vertical alinement to make a sinuous passage for the products of combustion, a series of water-tubes located below the lowermost transverse plate, a series of transverse water-tubes located above the uppermost transverse plate and a series of longitudinal water-tubes located between said transverse plates, spaces being left at the sides of said transverse plates for the more direct upward passage of portions of products of combustion.

7. A steam-boiler having chambered walls formed of inner and outer metal plates and having water-tubes connecting opposite points of said walls, the outer plates of said walls being formed with openings opposite the ends of said water-tubes, suitable covers for said openings and an external plate for protecting a number of said covers.

8. A steam-boiler having chambered walls formed of inner and outer metal plates and having water-tubes connecting opposite points of said walls, the outer plates of said walls being formed with openings opposite the ends of said water-tubes, and suitable covers for said openings, said covers being arranged upon the inside of said outer plates and being provided with bolts and crabs for holding them in position, and an external plate for protecting a number of said covers, bolts and crabs.

9. A steam-boiler having chambered walls surrounding a fire-box and a space for the passage of products of combustion, a raised bridge-wall at the rear of said fire-box, a transverse deflecting-plate extending from the front wall to a distance beyond the line of the bridge-wall and at a point above said bridge-wall, a second deflecting-plate extending from the rear wall to a point adjacent the forward part of the boiler, a series of transverse tubes located above the bridge-wall and at the rear of the fire-box, a series of longitudinal water-tubes extending between the transverse deflecting-plates, and a series of transverse water-tubes located above the upper deflecting-plate, said water-tubes connecting the chambered walls of the boiler at opposite points.

10. A steam-boiler having front, rear and side vertical chambered walls, forming and entirely surrounding a fire-box and combustion-chamber, a steam-drum located at the 5 top of the boiler and having open spaces adjacent its ends connecting with the chambers of the front and rear walls, water-tubes connecting said steam-drums to the chambers of the side walls and arched plates connected to 10 said drums and said side walls and inclosing said water-tubes within the combustion-chamber.
11. A steam-boiler having chambered walls formed of inner and outer plates, water-tubes 15 connecting opposite points of said chambered walls and hollow stay-bolts located between said inner and outer plates at points adjacent the ends of said water-tubes.
12. A steam-boiler having chambered walls 20 and having a steam-drum located at its top, a series of water-tubes connecting the lower portion of said steam-drum to the upper portion of said chambered walls and arch-plates leading from the sides of said steam-drum to 25 the tops of said chambered walls and inclosing said water-tubes.
13. The combination with the steam-boiler having chambered walls and a steam-drum connected thereto, of water-drums located 30 upon opposite sides of said steam-drum, and pipes connecting said drums.
14. A steam-boiler having chambered walls and a steam-drum connected thereto in combination with water-drums located at opposite sides of said steam-drum, pipes connecting 35 said drums, and arch-plates extending over said water-drums.
15. A steam-boiler having chambered walls having a steam-drum located at its top and having a series of water-tubes connecting the 40 lower part of said steam-drum to the upper part of said chambered walls and water-drums located upon opposite sides of said steam-drum, pipes connecting said drums and arch-plates inclosing said water-drums. 45
16. A steam-boiler having chambered walls and a steam-drum connected thereto in combination with water-drums located upon opposite sides of said steam-drum, the front end of said water-drums being sustained by the 50 front wall of the boiler, suitable brackets for sustaining the rear ends of said water-drums and pipes connecting said steam and water drums.
17. A steam-boiler having chambered walls 55 and a steam-drum connected thereto in combination with water-drums located at opposite sides of said steam-drum, arch-plates extending oversaid water-drums, pipes connecting said drums and a blow-off pipe leading 60 from the outer ends of said water-drums.
18. A steam-boiler comprising chambered walls and having a steam-drum located at its top, a series of water-tubes extending between opposite points of said chambered walls and 65 arch-plates extending between the tops of said walls and said steam-drum and an arched smoke-flue spanning said steam-drum at its rear end and connected with the space for the passage of products of combustion.

GEORGE THOMPSON.
